UNITED STATES PATENT OFFICE.

GEORGE S. COOPER, OF SALEM, OHIO.

ENGINE.

1,216,777.

Specification of Letters Patent. Patented Feb. 20, 1917.

Original application filed March 11, 1913, Serial No. 753,545. Divided and this application filed July 13, 1914. Serial No. 850,572.

To all whom it may concern:

Be it known that I, GEORGE S. COOPER, a citizen of the United States, and a resident of Salem, State of Ohio, have invented certain new and useful Improvements in Engines, of which the following is a specification accompanied by drawings.

This invention relates to steam engines, and is shown in connection with a superheated steam power unit, the superheater construction of which forms the subject matter of my copending application, Serial No. 753,545, filed March 11, 1913, and this is a division of said application.

One object of the present invention is to afford improved means for mounting the engine on the boiler and provide for longitudinal play between portions of the engine frame and its supports. Another object of the invention is to produce a new and more efficient construction of engine frame to meet the requirements especially of superheated steam power units of the type shown in the drawings, although the engine described herein is not of course limited in its use to such units.

In the drawings:

Figure 1 is an elevation, partly in longitudinal section, of a superheated steam power unit embodying the invention;

Fig. 2 is a plan view of the unit with a portion of the smoke box broken away;

Fig. 3 is a detail transverse sectional view on line 3—3 of Fig. 1 showing the mounting of the cylinder and of the engine bed on one boiler saddle;

Fig. 4 is a detail end elevation of the skeleton frame for supporting the cylinders, and Fig. 5 is an enlarged detail view partly broken away, showing the mounting for the cylinders.

In the type of apparatus shown in the drawings, A represents a steam boiler of the horizontal fire tube type having the combustion chamber B and fire tubes C which are removable from the boiler shell. The waste fuel gases are discharged into one compartment D of a smoke box E and finally find their way after circulating as desired, to the draft flue F provided at the lower portion of the smoke box and leading to the chimney.

A steam engine G preferably of the horizontal reciprocating type is mounted above the boiler and provided with one or more cylinders, in this instance, a compound en-

gine being shown having the high pressure cylinder H and the low pressure cylinder J extending into another compartment K of the smoke box. These cylinders H and J as shown are jacketed by the waste fuel gases. 60

The main engine bed, as shown in Fig. 2, comprises a Y-shaped frame U having the main body portion 7 and the legs 8. Both the main body portion and legs are provided with feet adapted to be supported on main 65 auxiliary saddles mounted on the boiler. The main saddle 9 supports the foot 10 at one end of the bed (see Fig. 1) while the auxiliary saddle 11 supports the foot 12 at the main body portion of the bed adjacent 70 the cylinders. Wooden strips or preferably hard fiber strips 13 and 14 are preferably interposed between the feet and saddles respectively and the foot 10 is rigidly secured to the saddle 9 by any suitable means at one 75 end of the bed, but the main body portion of the bed is free to slide longitudinally at the cylinder end on the saddle 11 due to longitudinal expansion. In Fig. 3, a detail of the construction of the main body portion 80 of the bed at the cylinder end is shown, in which the foot 12 is provided with beveled flanges 15 secured to the saddle as by means of the beveled clamps 16 and bolts 17, so that the foot 12 is held upon the saddle, but has 85 slight longitudinal play relative thereto to compensate for different co-efficients of expansion between the parts.

Provision is also afforded for slight longitudinal play or movement between the 90 bearing foot 18 of the low pressure cylinder casing and the supporting block 19 carried by the skeleton frame q, of substantially horse-shoe form, which supports the cylinders. This frame q is carried in a saddle r. 95 As shown in this instance, machine screws 20 hold the foot 18 upon the block 19 and said screws pass through holes 21 in the block of larger diameter than the screws, so that slight longitudinal play is permitted 100 between the parts.

The main engine bed is especially designed to provide for the strains met with in such units and the engine is mounted in such a manner as to provide for strains.

In order to make the application of the invention to a superheated steam power unit clear, a brief description will be given of the superheater, as follows:

In the compartment D of the smoke box 110

are arranged the high pressure superheater L, and the low pressure superheater O, arranged end to end, and the waste fuel gases traverse said superheaters, emerging in the space P of the compartment D. A baffle *a* causes the gases to pass upwardly in the direction of the arrows, and said gases are directed by the baffles *b* and *c* first through the space Q around the low pressure cylinder J, thence across and downwardly through the space R around the high pressure cylinder H, and thence downwardly around the coils of the high pressure superheater L and out through the draft flue F, all as indicated by the arrows. Steam passing from the boiler through the main pipe *d* is led to the rear end of the high pressure superheater L, thence through the coils of the superheater and by pipe *e* to the high pressure cylinder H. The exhaust steam from the high pressure cylinder H passes through pipe *f* to the rear and lower end of the low pressure superheater O and thence passes upwardly within the said superheater around the horizontal tubes and out by pipe *g* to the low pressure cylinder J, from which the exhaust steam may be taken to any suitable auxiliary apparatus (not shown).

The low pressure superheater O is kept free of oil by means of the drain cock *h* having a valve handle *j* outside of the smoke box. The drainage is effected by means of the pipe *k* extending outside of the smoke box. A track S, mounted in the compartment D, has one end secured to the boiler header *o*, while the other end is hung by means of the rod *p* from the skeleton frame *q*. Both the high and low pressure superheaters are carried on rollers *s* running on the track S, so that the superheaters may be run in and out of the superheater compartment through a door T at one end, having a baffle *t*. The high pressure superheater L is strapped by the U-shaped straps *u* to the I-beam V, and the rollers *s* are mounted on hangers *w* connected to said I-beam. The rollers *s* for the low pressure superheater O are mounted on hangers *x* connected directly to the superheater casing. The steam pipes

d, e, f and *g* are provided with suitable couplings by means of which the pipes may be disconnected.

2 represents a steam pipe provided with the perforated radial arms 3 and 4. This pipe 2 is mounted in bearings in the frame 55 4 and in the door T, and a hand-wheel is provided outside of the smoke box for rotating the cleaning device (not shown). Steam is admitted to the pipe 2 by the pipe 6 and by rotating the radial arms 3 and 4, 60 both the boiler flues and the superheaters may be cleaned.

I claim and desire to obtain by Letters Patent the following:

1. In an engine, the combination with a 65 horizontal boiler, of saddles mounted thereon forming main and auxiliary bearings, an engine having a portion of its bed fixedly supported on the main bearing saddle and having the main body portion of its bed 70 free to slide upon the auxiliary bearing saddle, the engine and its bed being arranged over the boiler, a frame independent of the boiler for supporting the engine cylinders, and provision affording relative longitudinal play between the cylinders and said independent support.

2. In an engine, the combination with a horizontal boiler, of saddles mounted thereon forming main and auxiliary bearings, an 80 engine having a substantially Y-shaped bed, the legs of said bed being fixedly supported upon said main bearing saddle, and the main body portion of the bed being free to slide upon the auxiliary bearing saddle, the engine and its bed being arranged over the 85 boiler, a frame independent of the boiler for supporting the engine cylinders, and provision affording relative longitudinal play between the cylinders and said independent support.

In testimony whereof I have signed this specification in the presence of two subscribing witnesses.

GEORGE S. COOPER.
